ARCHIE L. STROUT, OF STOCKTON, CALIFORNIA.

AUTOMATIC STABILIZER FOR AEROPLANES.

1,314,913.

Specification of Letters Patent. Patented Sept. 2, 1919.

Application filed March 7, 1918. Serial No. 220,916.

To all whom it may concern:

Be it known that I, ARCHIE L. STROUT, a citizen of the United States, residing at Stockton, in the county of San Joaquin, 5 State of California, have invented certain new and useful Improvements in Automatic Stabilizers for Aeroplanes; and I do declare the following to be a clear, full, and exact description of the same, reference being had 10 to the accompanying drawings, and to the characters of reference marked thereon, which form a part of this application.

This invention relates to improvements in aeroplanes and particularly to the safety appliances thereof. The object of the invention is to produce an automatic stabilizer for aeroplanes including a means for positively moving the balancing planes or ailerons in direct relation to the inclination of the lifting planes relative to the horizon or, in turning the machine, in direct relation to the position of the stabilizing pendulum resulting from the combined force of gravity and centrifugal force which acts against the 15 pendulum when the machine is steered into a curve. By this means, when the lifting planes tilt or incline from horizontal position in one direction, the balancing planes will immediately and automatically be set 20 in opposed counter-balancing relation thereto and thus force the lifting planes into return motion toward proper horizontal position. As this latter movement is taking place, the mechanism automatically causes 25 the balancing planes to positively follow-up this return movement in such a manner that the counter-balancing effect is gradually lessened as the lifting planes approach the point of equilibrium and when such point 30 is reached, the said balancing planes also reach normal horizontal position. Thus the liability of the lifting planes to careen toward the opposite side, due to the failure of the balancing element to reach normal position 35 at the same time the lifting planes do, is entirely eliminated, and an easy, positive and automatic control of the aeroplane is assured.

On curves, when the pendulum is swung 40 out of perpendicular to the lifting planes as the machine is turning, this will automatically set the ailerons to act to set the lifting planes back into perpendicular with the pendulum and thus give the banking effect necessary to quick and effective turning.

A further object of the invention is to

produce a simple and inexpensive device and yet one which will be exceedingly effective for the purposes for which it is designed.

These objects, I accomplish by means of 60 such structure and relative arrangement of the parts as will fully appear by a perusal of the following specification and claims.

On the drawings, similar characters of reference indicate corresponding parts in 65 the several views.

Figure 1 is an elevation of the pendulum and automatic stabilizer link mechanism connected therewith.

Fig. 2 is an end view of the same.

Fig. 3 is a detached view, partly broken out and in section, of the fluid pressure controlled mechanism connected with the pendulum.

Referring now more particularly to the 75 characters of reference on the drawings, the numeral 1 designates the supporting frame which may be of any desired structure and mounted at a suitable point on the carriage of the aeroplane. Pivoted and suspended 80 centrally within this frame 1 is a slotted guide link 2. A supporting sleeve or bearing 3 is disposed through the slot of the guide 2 and is adapted to have longitudinal movement therein and to be fixed at any desired point by means of an adjustment nut 4 whereby the relative position of the pendulum, which is supported in said bearing, may be fixed to insure proper operation 85 thereof.

Turnable within this sleeve 3 is the shaft 5 of the pendulum 6, which pendulum is fixed to said shaft at one outer point. By reason of the shaft being turnable within the sleeve, this will give to the pendulum 90 a free horizontal swinging movement. It is also given a free vertical swinging movement by means of being hinged vertically to the shaft 5, as at 7.

At the opposite end of the shaft 5 is fixed 100 a slotted guide 8. The slot 8^a of this guide 8 receives a small wrist pin 9 on a crank 10 fixed to the stem 11 of a shutter valve 12 turnable within a valve casing 13. This valve casing 13 has an inlet 14 and an outlet 14^a diametrically opposite each other, the open and closed position of which is controlled by the valve 12. It also has two other communicating ports 15 and 16 which are likewise diametrically opposite each other 110 at right angles to the inlet and outlet 14 and 14^a, respectively. The port 15 communicates

with one end of a cylinder 17 and on one side of a piston 18 movable within said cylinder 17. The other port 16 communicates with the opposite end of the cylinder 17 and 5 on the opposite side of the piston 18.

A piston rod 19 is connected with the piston 18 and extends into active connection with the levers governing and controlling the position of the balancing planes or ailerons. These may be of any common construction, hence I do not here enter into a detailed description or illustration of the same.

Fixed to the piston rod 19 is a bracket 20 15 pivotally connected to which, as at 21, is a connecting rod 22 pivotally connected at its opposite end to the link 2, as at 23.

Fluid pressure, such as oil, air, water, or 20 any other desired form of such pressure, is maintained constantly in the inlet pipe 14 and returns through the outlet pipe 14^a by means of any desired structure, as for instance a suitably operated pump A and constant pressure regulating tanks B. These 25 may be of almost any form, however, so I will not enter into a detailed description of their structure and operation.

The operation of the device, describing 30 first the method of moving the ailerons in direction relation to the horizontal position of the lifting planes is as follows:—

As the lifting planes incline out of horizontal position, the frame 1 which carries the cylinder 17 and valve casing 13 and its connected parts inclines with such planes, while the pivotally suspended pendulum is held perpendicular to the horizon by force of gravity. This causes the casing 13 to move 35 relative to the valve 12. Assuming that the lifting planes tip toward the right-hand side of the mechanism, as shown in the drawings, this will open communication from the inlet pipe 14 through the valve casing 13 and port 16 into the cylinder 17 at the right-hand side 40 thereof. Thus, the fluid pressure will act against the piston 18 to cause it to force the piston 19 toward the left-hand side. This will cause the piston rod 19 to act on the control levers of the balancing ailerons to cause 45 them to be set immediately in a position to counter-balance the lifting planes and force them back toward horizontal position. At the same time, through the medium of the bracket 20 and the connecting rod 22, as the 50 ailerons are being set in counter-balancing position, the suspended link 2 is being forced to the left, which action continues until the pendulum 6 has been forced to the left a distance sufficient to close the valve 12. This, 55 of course, shuts off the pressure. Also, this action sets the point of suspension of the pendulum at a new point which is in direct relation to the new center of air pressure against the lifting planes. Hence, as the 60 lifting planes are forced backwardly toward

horizontal position by the counter-balancing planes, the mechanism instantly acts under the force thereof to incline in the opposite direction with respect to the suspended pendulum. Hence, the action of the valve 12 is 70 reversed and communication is opened from the inlet 14 through the casing 13, through the port 15 into the left-hand end of the cylinder 17 and against the opposite side of the piston 18. Thus, as the lifting planes 75 are returned to normal position, the ailerons will be moved in direct relation thereto back to normal position. Thus, as soon as the lifting planes are in proper position, the counter-balancing effect will cease, as is very 80 necessary to efficiently and positively maintain the equilibrium of the aeroplane.

Describing now the effect and operation of the mechanism when driving the aeroplane in a horizontal curve, the combination 85 of the force of gravity and the centrifugal force occasioned by the movement of the aeroplane in such horizontal curve first throws the pendulum out of perpendicular to the lifting planes, which action, through the 90 medium of the mechanism described, sets the ailerons to cause the lifting planes to immediately tilt the aeroplanes in the proper position to bank the same against the air pressure as is proper in making short and accurate curves, and to prevent the skidding of the aeroplane in the air in a long sweep instead of making a direct positive curve. Then, after the curve is made, the mechanism will again right itself automatically by 95 100 means of the structure and operation fully set forth.

As the fluid pressure acts positively against one side of the piston 18, that on the opposite side exhausts through the opposite 105 port mechanism and through the outlet pipe 14^a back to the pump and pressure tanks.

While I have shown herein a fluid pressure for positively directing the action of the ailerons and the positioning link of the 110 pendulum, still in practice this may be carried out by other mechanical or electrical means, hence, I do not wish to be understood as limiting myself to this form of power, since the main essential element of the invention is the positioning link and the positive motive force for driving the ailerons and such link.

The pivotal connection of the pendulum together with its hinged connection with the pivotal shaft permits the same to perform its functions irrespective of any position which the aeroplane may assume even a completely inverted position.

From the foregoing description it will 125 readily be seen that I have produced such a device as substantially fulfills the objects of the invention as set forth herein.

While this specification sets forth in detail the present and preferred construction 130

of the device, still in practice, such deviations from such detail may be resorted to as do not form a departure from the spirit of the invention as defined by the appended 5 claims.

Having thus described my invention, what I claim as new and useful and desire to secure by Letters Patent is:—

1. An automatic stabilizer for aeroplanes
- 10 comprising a support mounted on the aeroplane, a slotted link pivoted to the support, a shaft adjustably mounted in the slot of such link, a pendulum hinged to the shaft whereby such pendulum may have a free 15 lateral and longitudinal swinging movement, and a positive motive force controllable by the position of the pendulum for operating the balancing planes of the aeroplane.
- 15 2. An automatic stabilizer for aeroplanes

comprising a support mounted on the aeroplane, a link pivoted on the support, a shaft journaled in the link, a pendulum hinged on one end of the shaft, a cylinder, a piston movable within the cylinder, a push rod on the piston projecting outside the cylinder, 20 a valve controlled port communicating with each end of the cylinder, an arm on the shaft connecting with the valve, and a link mechanism connected between the push rod and the first named link, the push rod being 25 connected with the balancing planes of the aeroplanes.

In testimony whereof I affix my signature in presence of two witnesses.

ARCHIE L. STROUT.
